UNITED STATES PATENT OFFICE.

LYMAN O. ORTON, OF PHILADELPHIA, PENNSYLVANIA.

GOVERNOR.

SPECIFICATION forming part of Letters Patent No. 288,728, dated November 20, 1883.

Application filed June 14, 1883. (No model.)

To all whom it may concern:

Be it known that I, LYMAN O. ORTON, a citizen of the United States, residing in the city and county of Philadelphia, State of Pennsylvania, have invented a new and useful Improvement in Governors, which improvement is fully set forth in the following specification and accompanying drawings, in which—

Figure 1 is a partial side view and partial vertical section of a governor embodying my invention. Fig. 2 is a plan view thereof, partly sectional.

Similar letters of reference indicate corresponding parts in the two figures.

15 My invention consists in improvements in a governor, whereby the change in the pressure of fluid occasioned by the variations of the load is adapted to regulate the speed.

Referring to the drawings, A represents a 20 rotary shaft which is suitably operated by the engine to be governed.

B represents the belt or band wheel, and C represents a radial arm of tubular or hollow form, the latter being firmly secured to said 25 shaft A, and the former being loosely fitted on the hub of said arm.

D D' represent lugs which project inwardly from the rim of the wheel B, and have between them the ends of the arm C.

30 In the shaft A is a passage, a, communicating with the bore of the arm C, and said shaft has also a bore, b, which is in communication with the passage a, and consequently with the arm C. The ends of the arm C are enlarged, 35 forming chambers C', the open ends whereof have fitted within them pistons E, which are adapted to bear against the lugs D of the wheel B.

Connected with the hollow portion of the 40 shaft A, and communicating therewith, is a pipe, F, the joint between the parts being suitably stuffed or packed, said pipe leading to a chamber, G, which is located above the governor-valve, and in the present case supported thereon. Within the chamber G is 45 fitted a piston or head, H, which is attached to the stem H' of said valve. Bearing against said head and the guide of said stem is a spring, J, adapted for raising the head H, and consequently the movable portion of the 50 valve.

K represents a supply-chamber which is connected with the pipe F.

L represents a check-valve fitted between said chamber K and pipe F, and M represents 55 a gage in communication with the pipe F. The chamber K is closed at top by a head or piston, K', which is held down by means of a weighted arm, N, suitably mounted, the weight being adjusted to a determined pressure. Wa- 60 ter or other suitable fluid is supplied to the chamber K, and fills the pipe F, chamber G, bore b, passage a, and the bore of the arm C and chamber C' thereof, the check-valve L being properly opened to permit the entrance of 65 fluid from the chamber K to the pipe F, the check-valve closing during the operation of the governor. When the engine is started, the shaft A is rotated, and the arm C carries around with it the wheel B, so that the pistons E are 70 brought in contact with the lugs D. As the load increases and the wheel B is thereby checked, the pistons are more forcibly pressed against by the lugs D and driven into the chambers C', thus exerting their pressure on 75 the fluid in the arm C and causing an increased pressure of the fluid in the chamber G, whereby the governor-valve is opened or operated to increase the supply of steam to the engine. When the load decreases, the pistons E are 80 correspondingly relieved, and thus permitted to move out of the chambers C', whereby the pressure of fluid in the arm C and chamber G is reduced, thus relieving the head H, and the governor-valve is operated to decrease the 85 supply of steam passing to the engine. Should there be an insufficient supply of fluid in the chambers C' G, &c., the valve L opens and permits fluid in the chamber K to enter the pipe F, said valve again closing when pressure 90 is exerted on the pipe.

It will be found that the governor operates with sensitiveness, and its reliability is furthered by maintaining a uniform supply of fluid, for which purpose the chamber K is 95 provided, as has been stated.

Having thus described my invention, what I claim as new, and desire to secure by Letters Patent, is—

1. A governor having a rotary fluid-chamber 100 with a piston therein, and a belt or band wheel engaging with said piston, whereby, by

the change of the load, the piston occasions varying pressure of the fluid in said chamber, the same being exerted on the governor-valve, substantially as and for the purpose set forth.

5 2. A rotary chamber, a piston in said chamber, a belt or band wheel rotated by said arm, and against which the piston abuts, a chamber with the head of the stem of the valve therein,

and a pipe forming communications between the two chambers, combined and operating substantially as and for the purpose set forth.

LYMAN O. ORTON.
